UNITED STATES PATENT OFFICE.

WILLIAM G. SEATON, OF KNOXVILLE, TENNESSEE.

PENCIL-CONTAINER.

1,377,097.

Specification of Letters Patent.

Patented May 3, 1921.

Application filed March 3, 1921. Serial No. 449,278.

To all whom it may concern:

Be it known that I, WILLIAM G. SEATON, a citizen of the United States, residing at Knoxville, in the county of Knox and State 5 of Tennessee, have invented a new and Improved Pencil-Container, of which the following is a specification.

This invention has reference to that class of novelties, more especially designed to be 10 attached to coat or vest pockets and adapted for holding, in a substantially self-locked manner, pencils, pens and other similar small articles, in position for readily inserting the pencils or pen holders so they 15 will be held self-locked and in such manner that they will not accidentally drop out and be lost and are so positioned that they may be readily reached when desired.

Primarily, my invention has for its purpose 20 to provide an improved container of the general type stated, of a relatively few parts, so arranged that a number of pencils and like articles can be carried and each individually held, separate from the others, 25 to facilitate the withdrawal and insertion of any desired one of such articles and whose body is shaped for being carried in the outer or top pocket of a coat or vest that is comparatively light in weight, and in which the 30 several parts are so formed that the complete container can be easily and economically manufactured and which, when applied for use, presents a neat appearance and will not unduly wear or injure the garment on which it may be carried.

Another object of my invention is to provide 35 a device of the character stated in which is included an outer thin metal casing which constitutes a closure for all parts 40 of the container excepting the top portion having the entrance openings, into which the pencils are received, and which includes a peculiarly shaped and integral clip portion for gripping the outer top edge of the 45 garment pocket to thereby hold the container body securely within the pocket.

With other minor objects in view, that 50 will hereinafter appear, my invention consists of a device of the kind stated, that embodies the peculiar features of construction and novel combination of parts, fully brought out in the following detailed description, specifically mentioned in the appended claims and illustrated in the accom- 55 panying drawing, in which:

Figure 1 is a perspective view of my invention, the container being shown as carried in the upper pocket of a coat.

Fig. 2 is a vertical section of the container, an inserted pencil and the self-locking 60 spring member being indicated in locked engagement in dotted lines, the spring member being also shown at its natural or expanded position across the pencil receiving bore or pocket, in full lines. 65

Fig. 3 is a top plan view of the container, the single fastening screw, hereinafter referred to, being indicated in dotted lines.

Fig. 4 is an inverted plan view, partly in horizontal section, several pencils, of different external contour, being shown as secured in their respective pockets of the container. 70

Fig. 5 is a perspective view of the upper end of the body portion of the container, the exterior casing being omitted. 75

Fig. 6 is a detail perspective view of the locking device with its multiple individual resilient clamping members.

Fig. 7 is a detail perspective view of the wedge slide for securing the locking device 80 in its operative position, shown in Figs. 2, 3 and 4.

In the practical development of my container the same is composed of substantially four parts adapted for being secured in the 85 assembled or operative condition by a single screw, and the said parts include a body portion 1 preferably cast, or otherwise formed, of aluminum to give the desired lightness of weight, an outer cup shaped casing that incloses all of the body 1, and its attached members presently mentioned, excepting the top or entrance end for the pencil, a single lock device, stamped or otherwise shaped from thin resilient steel, 90 95 and a keeper or slide that secures the lock device in its operative position upon and within the container body, as will be presently fully explained.

In practice, the container 1 is in the nature of an elongated flat portion, with its corners rounded, as at 10, whereby to snugly engage the opposite ends of the pockets in a way that it will not readily tear or wear out the said pocket, a smooth engagement of the 105 container being further provided for by the thin metal casing 2 that closes over the body 1, as best shown in Figs. 2 and 4 of the drawings.

The body 1 has a plurality of vertical bores 110

or passages 11, four being shown, that extend through the full length of the said body, and the said bores 11, excepting along one edge (the front) which is flattened, as shown at 12, and for reasons best explained, are round and of sufficient diameter that (when the container is arranged for holding lead pencils) the pencils can be easily inserted, point end down and without danger of breaking the points, the mouth of the several passages 11 being flared as at 13 to permit the easy and safe insertion of the pencil.

On the front side, near the top, the body 1 is formed with a series of downwardly and inwardly inclined, square shaped openings 14, there being shown one for each bore or passage 11 and these openings are disposed transversely of the body portion 20 and in horizontal alinement with a transverse dove-tailed groove 15 which merges with the several openings 14, as is clearly indicated in Figs. 2 and 5, the groove 15 being provided for the reception of a dove tailed keeper 3 that is endwise slidable into and forms a closure for the groove 15 and the openings 14, it being also provided with a transverse seat or recess 30 for snugly fitting over the upper slot end or finger grip 30 of the locking device 4, the function of which is clearly apparent by referring to Fig. 2 and whose structure is illustrated in detail in Fig. 6.

The locking device 4 is composed of a single body plate of resilient metal that is stamped or otherwise shaped to present a solid top end 40 which constitutes a convenient finger grip for holding the said device 4, when inserting it to its operative position within the container body 1, it having a series of inwardly bowed spring fingers 41 of such length and so separated that the individual fingers can be readily slipped through the several openings 14 when the slide 3 is removed, as shown in Fig. 5, it being understood that when the device 4 is inserted into the body 1 the fingers are bowed across the passages 11 in the body 1 in the manner clearly shown in Fig. 2, it 50 being apparent by referring to the said Fig. 2 that by extending the spring member 41 across the passages 11, as shown, a perfect clearance for the insertion of the pencils is at all times provided and in such manner 55 that the point ends of the pencils will engage the spring fingers 41 in a manner that will cause the said fingers to flatten out to the position shown in dotted lines on Fig. 2 and without danger of the pencil point 60 getting clogged or broken. The shape of the dove-tailed slide or keeper 3 with its seat 30 serves to holding the head or top end 40 of the spring lock 4 seated solid between the slide 3 and the adjacent bearing 65 face 16 of the body 1.

The cup shaped outer metal casing 2, preferably of thin steel, is shaped to snugly incase the body 1, the upper end of the said body 1 having a flange against which the upper edge of the casing closes and makes 70 a clean fit.

At the front upper edge the casing, when stamped up or otherwise shaped, is formed with a substantially semi-circular extension that is bent back to constitute a curved clip 75 70 whose lower edge is flared outwardly as at 71 to facilitate slipping said clip over the pocket edge, the clip, in practice, being sufficiently resilient to secure the device in the pocket against dropping out.

To provide against the container being easily pulled out of the pocket, however, a button 8 may be sewn along the upper front edge of the pocket, as shown in Fig. 1, and under which the curved clip may be hooked 80 85 or as shown, and to provide for extending the clip members above the upper end of the body the flange 17 thereof is cut out as at 17-17^a for such purpose.

It will be observed that when the parts 90 are assembled as in Fig. 2, the casing holds the keeper or slide member 3 in place and for holding the several parts that constitute the complete container, together, a single screw 9, best shown in dotted lines Fig. 3, 95 passes through the casing and screws into the body 1.

The casing 2 has an aperture 72 in the bottom which is provided for the insertion of a head pin, or other like instrument, to 100 remove by pushing up short pencil stumps that might drop to the bottom of the passage 11 in the body 1.

From the foregoing taken in connection with the accompanying drawing, the complete structure, the manner of its use and its advantages will be readily apparent to those familiar with the practical application of devices of this kind.

What I claim is:—

1. A container of the character described, comprising a body member having a passage throughout its length, an opening in one face near the open end thereof, which opening communicates with the body passage, a bowed spring finger plate insertible through the said opening in the body member and extended lengthwise of the body passage and normally bowed across the said passage, and the said spring finger adapted for being flatwise lengthened in the body passage as a pencil or other object is inserted into the top of the said body passage, and means interlockably connecting the upper end of the spring finger plate with the container body. 115 120 125

2. A container of the character described, comprising a body member having a passage throughout its length, an opening in one face near the open end thereof, which opening communicates with the body pas- 130

- sage, a bowed spring finger plate insertible through the said opening in the body member and extended lengthwise of the body passage and normally bowed across the said 5 passage, and the said spring finger adapted for being flatwise lengthened in the body passage as a pencil or other object is inserted into the top of the said body passage, means interlockably connecting the upper 10 end of the spring finger plate with the container body, the said interlocking means including a seat portion on the container body against which the upper end of the spring finger rests, the said body having a wedge 15 groove which extends across the entrance of the opening through which the spring member is inserted and a cup shaped casing that fits over the bottom, the ends and the sides of the container body.
- 20 3. A container of the character described, comprising a body member having a passage throughout its length, an opening in one face near the open end thereof, which opening communicates with the body passage, 25 a bowed spring finger plate insertible through the said opening in the body member and extended lengthwise of the body passage and normally bowed across the said passage, and the said spring finger adapted 30 for being flatwise lengthened in the body passage as a pencil or other object is inserted into the top of the said body passage, means interlockably connecting the upper end of the spring finger plate with the container body, the said interlocking means including a seat portion on the container body against which the upper end of the spring finger rests, the said body having a wedge 35 groove which extends across the entrance of the opening through which the spring member is inserted, a cup shaped casing that fits over the bottom, the ends and the sides of the container body, the said casing having a projected curved member that is bent back over the upper end thereof whereby to form a clip for attaching to a pocket edge, said 40 casing having an aperture in the lower end 45 that opens into the passageway through the body.
4. A container of the character described, comprising a body member having a passage throughout its length, an opening in one face near the open end thereof, which opening communicates with the body passage, a bowed spring finger plate insertible through the said opening in the body member and 55 extended lengthwise of the body passage and normally bowed across the said passage, the said spring finger adapted for being flatwise lengthened in the body passage as a pencil or other object is inserted into the
- top of the said body passage, means interlockably connecting the upper end of the spring finger plate with the container body, the said interlocking means including a seat portion on the container body against which the upper end of the spring finger rests, the 60 said body having a wedge groove which extends across the entrance of the opening through which the spring member is inserted, a cup shaped casing that fits over the bottom, the end and the sides of the container body, the said casing having a projected curved member that is bent back over the upper end thereof whereby to form a clip for attaching to a pocket edge, said 65 casing having an aperture in the lower end 70 that opens into the passageway through the body.
5. A device of the character described, involving a body formed with a plurality of adjacent passages that extend lengthwise of the body, said body near the upper end having a series of squared openings one for each body passage with which they communicate, a resilient member having a series 75 of spaced bowed spring members and a head portion, the bowed spring members being spaced apart and adapted for being inserted through the openings in the body and into the several passages in the body, and means for holding the said head portion with its fingers bowed across and extended the full length of their respective passages in the body.
6. As a new article, a container of the character described, said container comprising a body having a plurality of separated passages that extend lengthwise therethrough and spaced openings at one side near the upper end thereof that communicate with the passages in the body, a lock 80 device consisting of a resilient plate having a solid head portion and a series of spaced bowed spring fingers, one for each passage in the body, said fingers being adapted for insertion through the openings in the side 85 of the body and for extending lengthwise 90 of the body and for bowed across the body passages, the said body having a transverse wedge shaped groove along that portion having a series of side openings, a 95 wedge member endwise slidable into the wedge groove, and having a seat on its inner face for receiving the head portion of the spring finger equipped locking device and a cup shaped casing that takes over the 100 bottom, the sides and the ends of the body 105 and forms a closure for the wedge member.

WILLIAM G. SEATON.
